WATER HEATER

Filed Jan. 2, 1929

INVENTOR:

CHARLES GABRIEL O'HARA.

CHARLES GABRIEL UHAG
by Arthur C. Baigz,
Attorney.

UNITED STATES PATENT OFFICE

CHARLES GABRIEL O'HARA, OF NORRISTOWN, PENNSYLVANIA

WATER HEATER

Application filed January 2, 1929. Serial No. 329,715.

My invention is applicable to ordinary systems of domestic and industrial heating, for the purpose of utilizing the heat from the products of combustion which is ordinarily wasted by direct discharge to a chimney. As hereinafter described, my invention includes an auxiliary water heater which is a unit structure adapted to be self-supporting, but accessory to the flue conduit of an ordinary furnace; so that the products of combustion from such furnace pass thru the casing of the water heater on their way to the chimney. An essential feature of my present invention is a unitary water container, comprising a single casting affording the maximum exposure of its surface for absorption of heat from the products of combustion, and including water passages so arranged as to facilitate the rapid circulation of the water in the heater.

The form of my invention hereinafter described is applicable to steam, hot water, or vapor systems, using coal, oil, or gas for fuel, and my invention includes the various novel features of construction and arrangement hereinafter more definitely specified.

In said drawings; Fig. I is an elevation of a water heater conveniently embodying my invention.

Fig. II is a plan sectional view, taken on the line II, II in Fig. I.

Fig. III is a fragmentary elevation of the lower left hand side of the heater shown in Fig. I.

Fig. IV is a plan sectional view, taken on the line IV, IV in Fig. I.

Fig. V is a side elevation of the unit water container casting indicated in Figs. I, II, and IV, but differently connected.

In said figures, the unitary water container 1, which is conveniently formed of cast iron, includes two opposite, longitudinally extending and substantially cylindrical, manifolds 2 and 3 with their axes in parallel relation, and connected by transverse conduit members 5 and 6 of respectively different patterns, but all inclined in parallel relation with each other and in oblique relation to the axes of said conduits 2 and 3. Said conduits 2 and 3 have hollow, substantially conical, projections ex-

tending laterally therefrom, in alignment with said conduits 5 and 6, and respectively indicated at 8 and 9. Each of the transverse conduits 5 has similar conical projections 11 extending laterally therefrom, intermediate 55 of said projections 8 and 9. However, each of said conduit members 6 has two similar hollow conical projections 12 extending laterally therefrom between the projections 8 and 9 local thereto; so that said projections 60 are of respectively different length and disposed in staggered relation upon the adjoining transverse conduits 5 and 6 and form between them irregular tortuous flue passages 65 of different areas at different regions thereof to baffle the products of combustion from which the heat is to be absorbed.

Said unitary water container 1 has, at respectively opposite ends thereof, pairs of internally screw threaded flanges 14 and 15, 70 with their axes at right angles to each other for selective connection with water pipes 16 and 17, which may be connected therewith either parallel with, or transversely to, the axes of the respective manifolds 2 and 3. 75 Such of the pipe socket flanges 14 and 15 which are not used, are closed by ordinary pipe plugs 18, as indicated in Fig. I.

In order to adapt said unitary water container 1 to be supported with its manifolds 2 and 3 either in vertical or horizontal position, I provide the internally screw threaded sockets 21 and 22 which may be selectively connected with the supporting standard 23, which may, conveniently, be a piece of ordinary pipe extending axially from a cast iron base plate 24 with which it is in screw threaded connection.

Said unitary water container 1 is also conveniently provided with radially extending 90 projections 26 and 27, respectively at right angles to each other, so as to space said container in concentric relation with the inclosing casing 29 which is, preferably, a cylindrical metallic shell. Such shells may be 95 formed of primarily plane sheets of metal, welded or riveted at their contiguous edges.

Said casing shell 29 has semicircular recesses 30 at its opposite end edges, and is provided with opposite end closures 31 and 32 100

which are, conveniently, alike and formed of cast iron. Each of said closures 31 and 32 has, at its edge, a semicircularly recessed flue port 33 adapted to register with one of said casing recesses 30, and the substantially circular port thus formed is adapted to selectively register with flue fittings 34, which are alike, and reversible with respect to said recesses 30 and 33.

10 Each of said fittings 34 has an annular flange 35 for connection with ordinary cylindrical sheet metal flue pipes, indicated respectively at 36 and 37 in Fig. I, and semicircularly recessed port openings, with edges 38 and 39 in relatively transverse planes, respectively extending parallel with, and at right angles to, the axis of said flange 35. The construction and arrangement of said closures 31 and 32 and said flue fittings 34 are such that the latter may be operatively connected with the heater casing 29 with the axes of their flanges 35 parallel with the axis of said casing 29, as indicated at the lower portion of Fig. I, or with such axes extending radially at right angles to the axis of said casing; as indicated at the upper portion of Fig. I. Said fittings 34 may be detachably connected with the end closures 31 and 32 by screws or bolts 42.

I find it convenient to provide each of said fittings 34 with a hand hole 44, thru which the container 1 may be reached to remove therefrom deposits of ash, dust, or soot, which are heat insulating. Said holes are normally closed by caps 45, detachably secured by screws 46, or other suitable fastening means.

The construction and arrangement above described are such that the connection and mounting of such unitary water containers 1 and their casings in either vertical or horizontal position may be effected with the minimum amount of labor, in accordance with the construction, arrangement, and disposition of the flue pipes of the furnaces to which such heaters are adapted to be accessory. However, unitary water containers having such characteristic features as above contemplated may be inclosed in casings of any suitable character adapted to direct hot gaseous products of combustion with respect thereto. Moreover, such flue casings as above contemplated with flue fittings adapted for selective reversal as described, may be used for any purpose for which they are adapted.

Therefore, I do not desire to limit myself to the precise details of construction and arrangement herein set forth, as it is obvious that various modifications may be made therein without departing from the essential features of my invention, as defined in the appended claims.

I claim:

1. A unitary cast water container, comprising opposite parallel manifolds having hollow laterally extending projections upon opposite sides thereof; transverse conduit

members extending obliquely to the axes of said manifolds and connecting the latter in registry with the projections on said manifolds; said transverse conduit members having laterally extending hollow projections in respectively staggered relation; pairs of water ports at opposite ends of the respective manifolds, the axis of one port of each pair being parallel with the axis of its manifold, and the other port of that pair having its axis transverse to the axis of the manifold; spacing projections extending radially from said container and adapted to position said container in concentric spaced relation in a cylindrical casing inclosing it; and sockets for supporting means having their axes respectively parallel with and transverse to the axes of said manifolds; one of said sockets being intermediate of the length of one of the end transverse conduits, and the other socket being intermediate of the length of one of said manifolds; whereby said container may be selectively connected with horizontally extending and vertically extending water supply pipes.

2. A unitary cast water container, comprising opposite parallel manifolds having hollow laterally extending projections upon opposite sides thereof; transverse conduit members extending obliquely to the axes of said manifolds and connecting the latter; said transverse conduit members having laterally extending hollow projections in respectively staggered relation; pairs of water ports at opposite ends of the respective manifolds, the axis of one port of each pair being parallel with the axis of its manifold, and the other port of that pair having its axis transverse to the axis of the manifold; spacing projections extending outwardly from said container and adapted to position said container in spaced relation in a casing inclosing it; and sockets for supporting means having their axes respectively parallel with and transverse to the axes of said manifolds; whereby said container may be selectively connected with horizontally extending and vertically extending water supply pipes.

3. A unitary cast water container, comprising opposite manifolds having laterally extending projections upon opposite sides thereof; transverse conduit members extending obliquely to the axes of said manifolds and connecting the latter; said transverse conduit members having laterally extending projections; water ports at opposite ends of the respective manifolds, the axis of one port being parallel with the axis of its manifold, and another port having its axis transverse to the axis of said manifold; and sockets for supporting means having their axes respectively parallel with and transverse to the axes of said manifolds; whereby said container may be selectively connected with hori-

zontally extending and vertically extending water pipes.

4. A unitary cast water container, comprising opposite parallel substantially cylindrical manifolds having hollow laterally extending projections upon opposite sides thereof; transverse conduit members extending obliquely to the axes of said manifolds and connecting the latter; said transverse conduit members having laterally extending hollow projections; said projections being of respectively different lengths and in staggered relation upon adjoining conduit members; whereby irregular tortuous flue passages are formed at the perimeter of said container; pairs of water ports at opposite ends of said container.

5. A unitary cast water container for a water heater; said container being of oblong configuration and having screw sockets for supporting means with their axes respectively parallel with and transverse to the greatest dimension of said container; whereby said container may be selectively supported with its greatest dimension vertical or horizontal.

6. The combination with a vertically extending standard having a screw thread at the top thereof; of a unitary cast water container of oblong configuration, having two screw threaded sockets respectively at the long and short sides thereof, adapted for selective engagement with said standard; whereby said container may be selectively supported with its greatest dimension vertical or horizontal.

7. A unitary cast water container comprising opposite parallel substantially cylindiform manifolds and a series of parallel transversely extending conduit members connecting said manifolds; said transverse conduit members having laterally extending hollow projections, of different lengths, with flue passages of different dimensions between them, at the perimeter of said container and in staggered relation upon the respective conduits, forming tortuous flue passages from end to end of said container, of different areas at different regions thereof.

8. The combination with a cylindrical flue casing; of a unitary cast water container comprising opposite manifolds connected by a series of transversely extending conduit members; said conduit members having hollow projections extending laterally therefrom and terminating at a substantially uniform radial distance from the axis of said container; and projections on said container adapted to space said container in concentric relation with said casing.

9. A flue casing including a cylindrical shell having substantially semicircularly recessed openings at opposite end edges thereof; and closures extending transversely to the axis of said shell, and each having a substan-

tially semicircularly recessed opening at the circumferential edge thereof, in registry with one of said openings in said shell; and two flue fittings, each including an annular flange adapted for connection with a cylindrical flue pipe, and having an opening with substantially semi-circular edges in right angular relation, respectively in a plane parallel with the axis of said annular flange and in a plane at right angles to that axis; whereby said flue fittings may be connected with said casing openings with the axes of their annular flanges selectively disposed, parallel with the axis of said casing and transversely thereto.

10. A flue casing including a cylindrical shell having a substantially semicircularly recessed opening at one end edge thereof; an end closure extending transversely to the axis of said shell, having a substantially semicircularly recessed opening at the circumferential edge thereof, in registry with said opening in said shell; and a flue fitting including an annular flange adapted for connection with a flue pipe, and having an opening with substantially semicircular edges in right angular relation, respectively in a plane parallel with the axis of said annular flange and in a plane at right angles to that axis; whereby said flue fitting may be connected with said casing opening with the axis of its annular flange selectively parallel with the axis of said casing and transversely thereto.

11. A flue fitting including an annular flange adapted for connection with a flue pipe, and having an opening with substantially semicircular edges in right angular relation, respectively in a plane parallel with the axis of said annular flange and in a plane at right angles to that axis.

12. An end closure for a cylindrical shell including a plane member extending at right angles to the axis of said shell and having a substantially semicircularly recessed opening at the circumferential edge thereof, adapted to register with a similar opening in the circumference of said shell, and form a substantially circular flue port.

In testimony whereof, I have hereunto signed my name at Norristown, Pennsylvania, this 26th day of November, 1928.

CHARLES GABRIEL O'HARA.
